(57) **CLAIM**

The ornamental design for an oil pump housing, as shown and described.

DESCRIPTION

FIG. 1 is a first perspective view of a first design of an oil pump housing;

FIG. 2 is a second perspective view of the design of FIG. 1;

FIG. 3 is a front view of the design of FIG. 1;

FIG. 4 is a rear view of the design of FIG. 1;

FIG. 5 is a first side view of the design of FIG. 1;

FIG. 6 is a second side view of the design of FIG. 1;

FIG. 7 is a top view of the design of FIG. 1; and,

FIG. 8 is a bottom view of the design of FIG. 1.

In the drawings, the broken lines depict portions of the oil pump housing that form no part of the claimed design.

1 Claim, 8 Drawing Sheets
